(57) **CLAIM**

The ornamental design for a reagent pack, as shown and described.

DESCRIPTION

FIG. 1 is a top, front, right side perspective view of the reagent pack of the new design.

FIG. 2 is a front elevation view thereof.

FIG. 3 is a rear elevation view thereof.

FIG. 4 is a left side elevation view thereof with the thickness of the reagent pack shown at an enlarged scale.

FIG. 5 is a right side elevation view thereof with the thickness of the reagent pack shown at an enlarged scale.

FIG. 6 is a top plan view of FIG. 1; and,

FIG. 7 is a bottom plan view thereof.

1 Claim, 4 Drawing Sheets

FIG. 2

FIG. 6

FIG. 3

FIG. 7

FIG. 4

FIG. 5
